SPRAYER

Irving J. Amato, Pittsfield, Mass., assignor of one-half to Edward F. Fahey, Pittsfield, Mass.

Application July 11, 1934, Serial No. 734,669

1 Claim. (Cl. 299—88)

My invention consists in the combination of a sprayer which is constructed and operates without the use of a tube extending into a liquid receptacle.

5 The primary object of the invention is to provide a sprayer without the use of a tube extending into the liquid receptacle, and so constructed that all the liquid in the liquid receptacle may be used or sprayed by the simple method of changing the angle or inclination of the liquid receptacle when spraying, and to prevent any of the liquid from being drawn into the air pump.

Another object of the invention is to provide a sprayer with a ball valve located in a casing on 15 the inside of the air pump, and the ball valve so constructed to operate alternately when a pressure of air is drawn in and forced out of the air pump, thus preventing any of the liquid entering the air pump and interfering with the action of the plunger.

20 My invention may be used for varied purposes, such as spraying disinfectants in the home or sick room, and also for spraying vines or plants, and also to prevent evaporation of the liquid within 25 the liquid receptacle.

The invention also consists in certain other features of construction and in combination and arrangement of the several parts, to be herein-after specifically described, illustrated in the accompanying drawing and set forth in the appended 30 claim.

Referring to the drawing, in which like numerals of reference designate like parts in the several figures:

- 35 Figure 1 is a plan view.
- Figure 2 is a side elevation view.
- Figure 3 is a front elevation view.
- Figure 4 is a central vertical section through Figure 3.
- 40 Figure 5 is a front view of the ball valve.
- Figure 6 is a sectional view of the ball valve.
- Figure 7 is a modified means of regulating the air within the plunger.
- Figure 8 is a sectional view of Figure 7.
- 45 Referring to the drawing, 1 indicates a liquid receptacle which may be either a bottle or a metal container, and in shipment is provided with a screw cap or cover similar to the cap or cover 2 shown on the drawing. The numeral 2 indicates a cap or cover that screws onto the liquid receptacle 1, and is provided with a gasket 3, on the inside, to prevent the liquid from leaking. A spray tube 4 extends through the cover 2 a short distance beyond the gasket 3 and is fitted to the 50 cover in an air-tight manner. By using a short

tube that does not depend into the liquid receptacle, I am able with my device, to use all of the liquid without any waste which is the case in the ordinary sprayer.

The pump 8 is provided with an inner casing 13 5 that is sweated to the pump in an air-tight manner, a ball valve 14 is sweated to the casing 13 also in an air-tight manner. This ball valve consists of the body 14 and is provided with the hole 17 that runs therethrough. A ball 18 is inserted 10 in the upper part of the body 14 and is fitted to the lower part of the hole 17 and said hole forms a seat for the ball 18. There is enough clearance 15 in the upper part of the hole 17 so that the ball 18 is free to pass up and down when agitated. The top of the hole 17 is slightly peened over, as indicated by the numeral 19, so that the ball may not pass therethrough.

In Figures 7 and 8 I have shown a modified form of valve used with my device. This consists 20 of the casing 20 which is inserted in the barrel of the air pump 8 in a similar manner as the casing 13, a disk valve 21 is fastened to the casing 20 by means of the valve stem 22 which is inserted through the hole 23 in the casing 20 and 25 peened over on the end, as indicated by the numeral 22, to hold it in position. This valve operates in a similar manner as the ball valve 14.

My device operates in combination with an air pump comprising the pump 8 with a plunger 15 30 operated by means of the rod 9 and the handle 10. The pump is provided with a cap 6, indented as indicated by the numeral 5, so that the top of the spray tube 4 may be placed in close proximity to the air hole 12 in the cap 6. The air pump is securedly fastened to the top of the cap or cover 2 by sweating or other means. The numeral 11 indicates the air inlet to the pump. The cap 6 is provided with an inner casing 13, forming an air chamber between the cap 6 and the inner 35 cover 14 so as to prevent any liquid from being sucked into the pump.

The device is operated as follows: As the contents of the receptacle are being lowered, the operator tilts or inclines the receptacle causing 45 the liquid to enter the spray tube 4. When the plunger 15 is drawn up the pump barrel 8, the ball 18 will be drawn into the seat formed by the hole 17 thereby preventing any liquid that may have been deposited in the pump, between the cap 6 50 and the casing 13, and also any liquid being drawn from the spray tube 4 into the barrel of the pump 8. This is a very decided advantage as most of the plungers in the ordinary pumps get out of order or do not work properly because of the effect 55

of the liquid drawn into the pump barrel and against the plunger.

What I claim is:

5 In an apparatus for spraying liquid, an air pump comprising a pump barrel having a plunger therein and a plunger rod and handle extending from one end of said barrel for reciprocating said plunger, a cap closing the other end of said barrel, said cap having a small air outlet hole there-

through, a partition across said barrel spaced inwardly from said cap, and a check valve in said partition opening toward said cap, a container cover secured to said barrel, a spray tube extending from the interior of said cover and across the 5 outer face of said cap to a point adjacent said air outlet hole, and a liquid container removably secured to said cap.

IRVING J. AMATO.
